UNITED STATES PATENT OFFICE.

WILLIAM BURR GREGG, OF HACKENSACK, NEW JERSEY, ASSIGNOR TO THE GREGG COMPANY LTD., OF HACKENSACK, NEW JERSEY.

CAR-FRAME CONSTRUCTION.

Application filed December 12, 1927. Serial No. 239,370.

This invention relates to an improvement in railway car frame construction, particularly adapted to railway cars intended for the transportation of sugar cane and like products, which are to be discharged from the car by means of hoisting.

It is an object of the invention to provide a bolster and cross bearer construction in a car frame of the type described in which the top members of the bolsters or cross bearers act to reinforce and strengthen the bolster and cross bearer construction of the frame, and at the same time to provide a portion of the cleat floor of the car.

Another object of the invention is to provide a simplified and economical way of making a railway car frame bolster in which extra strength may be added to the bolster without a proportionate increase in cost thereof.

Other objects and advantages of the invention will appear as the description of the invention, with reference to the accompanying drawings, proceeds.

In the drawings which show certain preferred forms of embodiment of the invention:

Figure 1 is a top plan view of one end of a railway car frame with portions broken away to show the details of the bolster construction.

Figure 2 is a sectional view approximately on the line 2—2 of Figure 1.

Figure 3 is a sectional view approximately on the line 3—3 of Fig. 1.

Figure 4 is a sectional view of a portion of the car frame and floor on the line 4—4 of Figure 1.

In railway cars designed to carry sugar cane and the like, which is to be discharged from the car by hoisting, it is usual to have a cleat floor extending across the frame of the car, as illustrated in Figures 1 and 4. The cleats 10 serve to hold the cane, which is supported between the stakes 11, a sufficient distance above the car frame to enable chains to be passed under the cane and between the cleats, in order to enable the hoist the lift the load of cane from the car.

In previous cars of this construction, it has been customary to form the bolsters and cross bearers approximately flush with the top of the side sills 1 and of the center sills 2 and to apply the usual top cover plate to the bolster and apply the cleats 10, which are

usually of angle iron or wood construction, across the width of the frame without reference to the bolsters or cross bearers.

In my invention, however, I provide a special construction of cleats to be used as the upper cross members of the bolsters and cross bearer of the frame in such a manner as to reinforce and strengthen the bolster and cross bearer construction, eliminate the usual top cover plate for the bolster, and at the same time serve the normal function of the spacing cleats 10.

Figures 1 and 2 illustrate a normal diaphragm construction of bolster in which four diaphragms 3 extend between the side sills 1 and center sills 2 of the car, two at each side of the frame. These diaphragms 3 may be of the usual channel construction, having a vertical central portion 3^a, with horizontally extending flanges 3^b along the top and bottom and flanges 3^c along each end, the end flanges 3^c being riveted to the webs of the side and center sills 1 and 2, and the bottom flanges being riveted to the bottom cover plate 5. A pair of similar diaphragms 6 extends between the center sills 2 and are secured in position in the usual manner. To form the cleat floor of the car over the bolster a channel section 7, extending from side to side of the car frame, is provided. The web of the channel 7 adjacent each side is riveted to the top flanges 3^b of the diaphragms 3, and the top flanges of the diaphragms 6, serving the functions of the usual top cover plate, and the flanges 7^a of the channel 7 project upwardly above the frame of the car to act as cleats spacing the sugar cane or other load a sufficient distance above the car frame to permit hoisting chains to be passed therebeneath. The use of a channel section 7, having the upstanding flanges 7^a to act as floor cleats, is a substantial improvement over prior constructions, as this one piece channel section performs the functions of the top bolster cover plate and also of two floor cleats, giving a stronger bolster than the plated type and stronger cleats than separate cleats and also closes the space between the bolster diaphragms for the full width of the car frame, thereby preventing water and material from falling therethrough onto the car tracks.

A similar channel iron section 8, having upstanding flanges 8^a acting as spacing cleats, may be located over a cross bearer 105

which may be of any preferred construction and is illustrated as comprising a pair of channel diaphragms 9^a extending between the side and center sills 1 and 2, and a channel diaphragm 9^b between center sills.

The channel member 8 is preferably riveted to the top flange of the diaphragms 9^a and 9^b, and due to greater strength of the channel member over angle construction 10 such as indicated at 10, the cross bearers are materially strengthened, also the channel having two vertical flanges gives two supports to the car load whereas an angle gives only one support.

15 It is likewise feasible to use channel members such as the channels 8 and single diaphragms, such as the diaphragm 9^a and 9^b, to form the bolsters of light weight car frames, in which event the extra strength 20 added by the channel member 8^a becomes of great importance.

It will be understood that a channel member having vertically extending flanges can be used as floor cleats and also as the top 25 cross member of either a bolster or a cross bearer, with various other constructions of bolsters or cross bearers than those specifically illustrated and that all these modifications and changes are contemplated 30 within the spirit of this invention and the scope of the appended claims.

What I claim as my invention is:

1. In a railway car frame of the cleat floor type, side and center sills, cleats extending across the car frame, a double diaphragmed bolster with a channel top cross member extending across the frame with the flanges of the channel projecting upwardly above the sills.

40 2. In a railway car frame of the cleat floor type, side and center sills, cleats extending across the car frame, a double diaphragm bolster and a channel member providing a pair of upstanding cleats with a 45 web of the channel member extending between the diaphragms of the bolster and secured to the top flanges thereof.

3. In a railway car frame of the cleat floor type, side and center sills, cleats extending across the car frame, a double diaphragmed bolster with a channel top cross member extending across the frame with the flanges of the channel projecting upwardly above the sills, and one or more 55 cross bearers, each with a channel top cross member extending across the frame with

the flanges of the channels projecting upwardly above the sills.

4. In a railway car frame of the cleat floor type, side and center sills, cleats extending across the car frame, including cleats formed of channels having the channel webs lying horizontally and riveted or bolted to the sills and having the flanges protruding upwardly forming cleats to support the load.

5. In a railway car frame of the cleat floor type, side and center sills, cleats extending across the car frame, including cleats formed of channels having the channel webs lying horizontally and secured to the side sills and having the flanges protruding upwardly to support the load, and a double diaphragmed bolster with a channel top cross member extending across the frame with the flanges of the channel projecting upwardly above the sills.

6. In a railway car frame of the cleat floor type, a plurality of cleats extending from side to side of the car frame and channel sections, each provided with a pair of upstanding flanges acting as cleats, located above the bolsters and cross bearers and secured thereto.

7. In a railway car frame comprising side and center sills and having double diaphragm bolsters, a channel member extending from side to side of the car frame over the bolster diaphragms and spacing the distance therebetween, the web of the channel member being secured to the top flange of each bolster diaphragm with the flanges of the channel projecting upwardly.

8. In a railway car frame of the type described, the side and center sills extending longitudinally of the frame, diaphragm bolsters extending therebetween and a channel member extending across the width of the car frame secured to the top flange of the bolster.

9. In a railway car frame of the type described, side and center sills extending longitudinally of the frame, double plate bolsters extending therebetween and a channel member extending across the width of the car frame over the bolsters and between the plates of the bolster secured to the top of the bolster plate.

In testimony whereof I have affixed my signature to this specification.

WILLIAM BURR GREGG.
